PROCESS OF MAKING LEATHER FLOUR
FROM WASTE LEATHERRobert R. Emmitt, Williamsport, Pa., assignor of
one-third to W. Clyde Harer, Williamsport,
Pa.

Application July 19, 1938, Serial No. 220,137

5 Claims. (Cl. 83—94)

This invention relates to a process of making leather flour from waste leather and product therefrom and is an improvement over the process recited in an application filed by Robert R. Emmitt and Edward L. Schenck October 28, 1937, Serial Number 171,596, which became Patent No. 2,257,726 on October 7, 1941, covering a process of making from waste leather fibrous material and product therefrom, the object of this invention being to provide a process by means of which the fibrous material produced by the above referred to process can be converted into a flour substance having inherent qualities comparable with other resinous molded plastics when molded under the combined action of heat and pressure.

Prior to my invention it has been impossible to grind waste leather into powder having the characteristics of wood flour and the like and I have found that by compacting the pulp-like substance produced by the process as described in application Serial No. 171,596 with the pulp in a dry state, the pulp can be cut into granular form in the nature of powder such as wood flour and the like, which can be used to form articles and the like by molding without the use of a binder.

I have found that by extensive experimenting that waste leather can be ground by degreasing the same in order to form a fibrous material and that this fibrous material can be compacted into a sheet which can be fed slowly through rolls into a cutting machine where it is reduced in size by knife blade type of cutters running at high speed in order to obtain a shearing action of the knives so that the ends of the fibers are cut off in order to produce what I have termed "flour."

Other and further objects and advantages of the invention will be hereinafter set forth and the novel features thereof defined in the appended claims.

In carrying out my process of producing a leather flour from what I have termed waste leather, such as scrap leather and the like, this waste leather is disintegrated in an attrition mill of a special design so as to form a sponge-like material formed of sponge-like particles as the material is more or less shredded so that substantially the entire surface of each particle will be exposed in order to allow the degreasing solvent to thoroughly remove the oils and greases therefrom.

The material or substance thus formed, which is in the nature of a sponge-like material is deposited in vats and agitated and treated in a

counter-flow process with a solvent, as for example, ethylene dichloride, benzene, isopropyl ether, naphtha, methyl "Cellosolve," propylene dichloride and trichlorethylene, so as to remove the grease, residue and the inherent oils present and while I am aware that many processes are now in existence for degreasing material and recovering the solvent and the residue from the solvent, I have found that a steam heating process is satisfactory to remove the solvents from the sponge-like substance and that the solvents and oils can be recovered by distillation whereby these by-products will have a commercial value.

With the above degreasing process, I have found that practically 100% of the oils and greases are removed from the disintegrated leather.

The material with the solvent and oils removed is thoroughly dried, preferably by a passage of hot dry air through a rotary drum type of drier or other suitable types of continuous driers so as to reduce the moisture contents of the substance to the lowest practical minimum, for example, about $\frac{1}{16}$ of 1%.

The dry substance is then fed into a double plate attrition mill so as to grind the substance to reduce the size of the fibers whereby a pulpy mass is formed which can be used for various purposes such as to form articles and the like. The above method produces a fibrous mass free from grease disclosed in the above referred to application, Serial No. 171,596.

The pulpy mass of material in a dry state is then fed into a cutting mill where it is reduced in size by the knife blade type of cutters running at high speed which produces a shearing action so as to quickly cut off or bite off the ends of the previously formed fibers, which reduces the mass into granular form in the nature of flour, powder or the like.

The flour thus formed contains substantially 5 or 10% glucose which acts as a binder and by wetting this flour in order to form a plastic mass, the same when subjected to the combined action of heat and pressure, such as a thermoplastic hydraulic press, forms a material which is comparable with other resinous molded plastics having a sufficient tensile strength to stand 50 the strain to which it is subjected.

The wetting of the material is preferably accomplished by spraying and agitating so as to produce a plastic mass of the desired consistency, but I do not wish to limit myself to any particular method of wetting and agitating the mass as I

have found that this substance can be placed in a vat, sprinkled and agitated and just sufficiently enough water added to form a plastic mass of the desired consistency in order to allow it to be molded, pressed or rolled into the desired shape under the combined action of heat and pressure or pressure only.

I have also found that a plastic mass having the desired consistency can be produced by mixing the flour with water and then drying off part of the water so as to produce a plastic mass of the desired consistency which can be readily molded under the combined action of heat into the desired shape.

In the specification, the word "flour" is used to describe a granular substance, such as powder, wood flour or pigment; "degreasing" is used to describe the removal of substantially all grease, oil and residue; "drying" is used to describe the removal of moisture therefrom; "wetting" is used to describe the conversion of the dry mass into a plastic mass of the desired consistency; "molded" is used broadly to define giving a desired shape to the plastic mass whether this is accomplished by rolling or pressing, with and without heat; "cutting" is used to differentiate the powdering of the material by a cutting action rather than a grinding action; "fibrous material" is used broadly to describe a mass containing fibers; "waste leather" is used broadly to indicate leather having practically no commercial value.

In the drawing I have illustrated a flow sheet of one form of apparatus for carrying out my invention. The small pieces of leather are fed to the single plate attrition mill A where they are disintegrated. The disintegrated mass then passes to a receptacle B containing a solvent where it is agitated for removing the grease therefrom. The degreased particles then pass through solvent extractors C, D and E. The particles are then passed through indirect and direct driers F and G to remove substantially all the moisture therefrom. These dried particles are then fed into a double plate attrition mill H and are discharged therefrom as a soft felt-like mass of fibrous material. This felt-like mass is fed into a compacting apparatus J. The compacted mass is then fed into a knife blade type of cutting machine K and are discharged therefrom as flour. A solvent recovering device I is connected to the apparatus as clearly shown.

From the foregoing description it will be seen that I have provided a method of producing a leather flour which contains substantially 5 or 10% glucose which enables the flour to be molded under the combined action of heat and pressure into any desired shape so as to form articles of various characters without the use of a binder of any kind, which article will have a sufficient tensile strength to allow the material to be used for practically unlimited purposes, thereby utilizing a waste product in the form of waste leather to form a leather flour from which products can be formed.

What I claim is:

1. The process of making leather flour from

waste leather which is first mechanically disintegrating the leather, second degreasing the disintegrated leather mass of material, third drying the mass of degreased material, fourth compacting the dried mass of material and finally cutting the compacted mass into flour by a shearing action.

2. The process of making leather flour from waste leather which consists in first mechanically disintegrating the leather, second degreasing the disintegrated leather by a solvent, third removing the solvent and drying the mass, fourth compacting the resultant mass of material, finally cutting the compacted mass of material into flour by passing it through a knife blade type of cutting machine.

3. The process of making leather flour from waste which consists in first mechanically disintegrating the leather, second degreasing the disintegrated leather by a solvent, third removing substantially all of the solvent from the degreased mass, fourth drying the mass, fifth reducing the size of the particles of the mass by grinding, sixth compacting the resultant mass, finally passing the compacted mass through a knife blade type of cutting machine to reduce the fibers to flour.

4. The process of making leather flour from waste leather, which consists in first passing the scrap leather through a grinding machine for mechanically disintegrating the same into small shredded particles, second agitating the mass thus formed in a vat containing a solvent for substantially removing all the grease therefrom including the inherent animal oils, third removing substantially all of the solvent from the degreased mass, fourth passing the mass through a drying apparatus to remove substantially all the moisture therefrom, fifth passing the dried mass through a grinding machine for reducing the size of the fibers to a soft felt-like mass of fibrous material, sixth compacting the felt-like mass of fibrous material and finally passing the compacted mass through a knife blade type of cutting machine for reducing the fibers to flour.

5. The process of making leather flour from waste leather, which consists in first passing the scrap leather through an attrition mill for mechanically disintegrating the mass into small shredded particles, second agitating the mass thus formed in a vat containing a solvent for substantially removing all the grease therefrom including the inherent animal oils, third removing substantially all of the solvent from the degreased mass, fourth passing the mass through a drying apparatus to remove substantially all the moisture therefrom, fifth passing the dried mass through a double plate attrition mill for reducing the size of the fibers to a soft felt-like mass of fibrous material, sixth compacting the felt-like mass of fibrous material and finally passing the compacted mass through a knife blade type of cutting machine for reducing the fibers to flour.

ROBERT R. EMMITT.
